UNITED STATES PATENT OFFICE

2,635,524

AIR CIRCULATING OR VENTILATING UNIT

Ralph D. Jenkins, Bruce, Wis.

Application April 4, 1949, Serial No. 85,335

2 Claims. (Cl. 98—33)

1

This invention relates generally to means for air circulation, and more particularly to a portable air circulation unit comprised of a plurality of tiered sections, each section being tubular and interchangeable with the other sections, one section being equipped with a fan and other sections being equipped with various types of vents, air filters, and air valve means.

A primary object of this invention is to provide an air circulating unit which can be easily transported from place to place and used either with or without a window opening.

Another object of this invention, ancillary to the preceding objects, is to provide an air circulating unit which is adaptable for use with various sizes and types of windows and other openings, the flexible tubular adapter which is used to connect the unit with such a window opening being easily detached and representing novel structure in itself.

Another ancillary object is to provide an air circulating unit which may be used to force circulation of air within a space according to the positioning of the various sections relatively to each other, and the positioning of the unit in the space being heated, cooled or simply ventilated.

Still another object of this invention, touched on in the preceding objects, is to provide means for removing the hot air from the top of a room, drawing air from another room through a grate or the like, or otherwise circulating the air within a single room, it being understood that air eventually exhausted by the fan can be drawn from either the top, bottom, or intermediate part of the tiered sections, as the need may arise during the use of the device.

And a last object to be mentioned specifically is to provide a device of the character described herein which will be relatively inexpensive and practicable to manufacture, which is safe, simple and convenient to use, and which will give generally efficient and durable service.

With these objects definitely in view, this invention resides in certain novel features of construction, combination and arrangement of elements and portions as will be hereinafter described in detail in the specification, particularly pointed out in the appended claims and illustrated in the accompanying drawings, in which:

Figure 1 is a three-dimensional view of the assembled device, with the flexible tubular adapter removed;

Figure 2 is a similar view but showing a slightly different arrangement of the sections;

Figure 3 is a vertical sectional view, taken sub-

2

stantially upon the section line 3—3 in Figure 1; Figure 4 is a horizontal sectional view taken substantially on the line 4—4 of Figure 3;

Figure 5 is a diagrammatic view showing how the device is used to draw air from another room and to circulate this air within a room according to the desire of the operator;

Figures 6 and 7 are somewhat diagrammatic views showing how this invention is used as in 10 circulating the air within a room, and exhausting warm air from the top of a room, respectively; and

Figure 8 is a view of the above mentioned adapter, the view being best thought of as a 15 fragmentary top plan view, with portions of a wall with a window structure therein and portions of the adapter being broken away and the underlying parts being shown in horizontal section and in plan, in order to amplify the disclosure 20 of this invention.

Similar characters of reference designate similar or identical elements and portions throughout the specification and throughout the different views of the drawings.

25 Referring now to the drawings in detail, this invention includes a plurality of tiered sections indicated by the even numbers 10 to 28. These sections need not all be different from each other, but the section 10 is represented as having a base frame 30 of open construction, corner legs 32 which may be of angle iron secured to the base frame 30 and also secured to the main portion of the section 10, identified by the same reference numeral, in spaced relation to the base frame 30. The section 12 is provided with an

30 air filter comprised of any suitable foraminous material 34 contained within a pair of vertically spaced horizontal screens 36 and 38. The section 14 has air valve means incorporated therewith including a plurality of louvers 46 connected to and controlled by a manual control bar 48 extending exteriorly of the section 14. In this connection, it may be noted that the sections 12 and 14 may be substantially duplicated by the sections 35 24 and 26, the section 24 having an air filter comprised of the material 40 and screens 42 and 44, while the section 26 is equipped with a similar plurality of louvers 50 and control bar 52.

The sections 16, 18, 22, and 28 may all be similar, with the possible exception of the height thereof, while the section 20 is provided with a rotary fan 54 and a motor 56 therefor, the fan and motor being supported on a suitable bracket 58 and the fan having an outlet 60 leading to the 45 exterior of the sections. It will be noted that 55

the sections 16, 18, 22, and 28 may all be similar, with the possible exception of the height thereof, while the section 20 is provided with a rotary fan 54 and a motor 56 therefor, the fan and motor being supported on a suitable bracket 58 and the fan having an outlet 60 leading to the exterior of the sections. It will be noted that

each of the sections is formed with a seat on its upper end adapted to receive the lower end of another section. These seats may all be similar, and are indicated at 61 in Figure 3.

If reference be now had to Figure 7, and the Figure 8, it will be noted that a flexible tubular adapter 62 is provided for use with this air circulating unit and as a part thereof. The adapter 62 has a smaller end 64 securable to the outlet 60 by means of a suitable clamp means 66. The larger end 68 of the adapter 62 is provided with a resilient extensible elongated member 70 which may be a coiled spring fixed within a hem on the larger end 68 of the adapter, and since the adapter is constructed of flexible material, this larger end 68 may be considered as definitely extensible and contractable. Wire shape-retaining hoops 71 may be secured in spaced relation within the adapter. A plurality of pegs with heads, indicated at 72 in Figure 8, will be provided in a window frame 74 representing environment wherewith this invention will be used, the headed members or pegs 72 being positioned in spaced relation around the part of the window opening in the wall 76 which is to be connected with the adapter, and it may be noted that the window sashes 78 may be shifted as indicated in Figure 7 and the adapter connected to only a portion of the window, when this is desirable. In any case, the resilient flexible elongated member 70 within the larger end 68 of the adapter holds this larger end in proper relationship with the headed members 72, while allowing easy removal of the adapter from the window when necessary, as in the case of a storm.

Figure 6 represents the use of the invention in causing circulation of air in a room, by drawing air into the top and bottom of the tiered sections and expelling the air from the outlet 60 of the section 20, this last-mentioned section being positioned at the desired height from the floor upon which the device rests. In this instance, the sections 12 and 24 may be used to filter the air and the sections 14 and 26 will have their air valve means in open position. In Figure 7, a second use of the invention is represented, it being presumed that the warm air is to be drawn from the top of a room and expelled through the adapter and through a window opening to the exterior of a building. In this instance, the section 26 will have its valve means open and the section 14 may have its valve means closed, and the section 20 will be positioned according to the height of the window above the floor upon which the unit rests.

In Figure 5 there is represented a use of this invention in which a floor 80 is provided with openings 82 and 84, one or both of which may be stairways, and a space heater 86 is positioned beneath one of these openings, with this invention positioned immediately above this same one of the openings. The warm air from the space heater 86 is then drawn into an upper room, circulated therethrough, and expelled to the other

opening 84 for a return to the space heater 86.

The operation of this invention will be understood, therefore, to be of a variable character, and the above examples of how the device may be used are to be considered as illustrative rather than limiting. The operation of the various elements of the invention will be clearly understood from a consideration of the foregoing description of the mechanical details thereof, taken in connection with the drawings, and further description would appear to be unnecessary.

Having described the invention, what is claimed as new is:

1. An air circulating unit comprising a series of stacked tubular sections open at their ends for the passage of air into the stack and including an intermediate relatively longest section having an air discharge in one side thereof and carrying within the same an exhaust blower fan discharging out of said air discharge, said series further including sections above and below the intermediate sections, one of the sections above the intermediate section and one of the sections below said intermediate section being provided with an air control louvered partition and with means for opening and closing the louvers in the partition each section in the series nesting detachably with an adjoining section whereby said sections are interchangeable to vary the height of the intermediate section in the stack.

2. An air circulating unit according to claim 1 wherein one of the sections above and one of the sections below said intermediate section includes an air filter extending across the same positionable by interchanging the sections above and below said intermediate sections at different distances from the sections provided with a louvered partition above and below the intermediate section.

RALPH D. JENKINS.
